Inventor.

John E. Peterson,

By his Attorney *John E. Peterson*.

UNITED STATES PATENT OFFICE

JOHN E. PETERSON, OF IRVINGTON, NEW JERSEY, ASSIGNOR TO VAN VLAANDEREN MACHINE COMPANY, OF PATERSON, NEW JERSEY, A CORPORATION OF NEW JERSEY

EXPANSION ROLLER

Application filed May 6, 1930. Serial No. 450,215.

This invention relates to devices, known as expansion rollers, for stretching cloth transversely. In the usual construction a cylinder is revoluble around a shaft and is equipped with a shell formed of slats or sections in two sets surrounding it which engage, through longitudinal slots in the cylinder, cams fixed on the shaft and adapted to move opposed slats in the two pairs toward and from each other as the cloth in travelling in frictional contact with the slat-formed surface of the device causes rotation of the structure formed by the cylinder and slats. My object is to improve devices of this class by increasing the efficiency and durability thereof, rendering the construction simpler and the parts more easily assembled and disassembled, and insuring smoother and quieter action and less resistance to rotation.

20 In the drawing,
Fig. 1 is a plan of the device;
Fig. 2 is a longitudinal section thereof;
Fig. 3 an end elevation;
Fig. 4 a section on line 4—4, Fig. 2;
25 Fig. 5 a plan of a fragment of the main shaft and a cam thereon; and
Figs. 6 and 7 transverse sections of one of the movable slats in planes cutting its two guide members.
30 An axial support is formed by a shaft 1 assumed to be held against rotation in any support and certain cam sleeves thereon to be described.

A cage revoluble around this support is 35 constructed as follows: 2 designates a pair of collar-like carriers penetrated by the shaft and 3 denotes rods parallel with the shaft and arranged in different radii from the axis of the cage and each penetrating the two carriers. The carriers and rods are secured together, against relative movement longitudinally of the rods, by split-rings 4 into which are tapped screws 5 which are screwed in against end flanges 2a on the carriers until 40 the consequent expansion of the split-rings causes them to exert clamping or binding pressure against the rods. In the preferred construction there are two other carriers 2a, split-rings 4a and screws 5a between the first two and united with the rods in the same way.

The shell is constructed as follows: Encompassing each end portion of this cage is a cylindrical set of slats 6. Each slat has affixed to it and extending inwardly a pair of guiding members 7 reaching between two of the rods and grooved in its opposite faces, as at 7a, the grooves being rounded and receiving both such rods so that thereby the slat is 55 slidable lengthwise of and on the rods; for securing each member 7 to the slat said member has a stem 7b penetrating a hole in the slat and having its outer end upset in the countersunk or enlarged part of the hole as shown in Figs. 6 and 7. The outer member 7 of each pair is equipped with a roller 8 at the inner side thereof. The rounded form of the grooves 7b insures movement of the slats with the minimum of binding and frictional resistance.

50 The bearings for the cage are afforded by outer races 9 secured with a driven fit in the several collars, inner races 10 arranged with a sliding fit on the shaft, and balls 11 which run in the grooves of the races.

Secured on the shaft by the set screws 12 are the sleeves 13 which, being outward of the carriers 2 and abutting the races 9 and 10, confine the cage against endwise displacement and which also have the circumferential cams 13a, here sinuous grooves. These 55 grooves receive the rollers 8 of the slats and are so formed and arranged as to cause each two alined slats, as in the rotation they pass any given radius, to move toward or from each other—see Fig. 1, for example, in which, due to the shape of the groove shown in Fig. 5, the slats appear in different stages, the pair at the top of the figure closest together and those at the bottom furthest apart.

Whatever the distance between the abutments formed by the sleeves 13 may be, since the carriers are adjustable lengthwise of the rods they may be set apart the required distance, for instance so that the abutments will, by abutting them, oppose any endwise movement of the cage, as shown in Fig. 2.

If the intermediate collars 2a are present there will usually be provided the intermediate slats 14, secured to them, as by the countersunk screws 15.

By this construction the device is more durable, may be manufactured at less expense and its action is smoother and accompanied by less friction and looseness of the parts than the ordinary construction. Assembly or disassembly is, moreover, more easily effected.

While, in accordance with usual practice, the shell in the example has both ends sectional or in the form of the movable slats, it is to be understood that the invention in its essence is concerned with at least one end of such shell being composed of the movable sections or slats.

An advantageous feature of my construction is that when any rod becomes worn by contact of the rollers 8 therewith it may be released and turned around its own longitudinal axis to present a fresh surface to the roller.

Having thus fully described my invention what I claim is:

1. In a device of the class described, a revolving cage comprising a carrier adapted to be journaled on an axial support penetrating the same and having a sinuous circumferential cam, round rods extending lengthwise of and arranged in different radii from the axis of the cage and bearing against the carrier, and means, acting transversely of the rods, to clamp them to the carrier, each rod being shiftable around its own lengthwise axis upon releasing said means, in combination with a shell encompassing said cage and having one end thereof composed of a circumferential series of sections individually movable on the rods toward and from the other end of the shell and each having means to engage the cam.

2. In a device of the class described, a revolving cage comprising a carrier adapted to be journaled on an axial support penetrating the same and having a sinuous circumferential cam, rods extending lengthwise of and arranged in different radii from the axis of the cage and bearing against the carrier, a split-ring and screw means engaging the carrier and split-ring and holding the latter in clamping engagement with the rods, in combination with a shell encompassing said cage and having one end thereof composed of a circumferential series of sections individually movable on the rods toward and from the other end of the shell and each having means to engage the cam.

3. In a device of the class described, a revolving cage adapted to be journaled on an axial support having a sinuous circumferential support and penetrating the carrier, said cage including cross-sectionally round rods arranged in a circumferential series, in combination with a shell encompassing the cage and having one end thereof composed of a series of sections individually movable toward and from the other end of the shell and

each having guiding means projecting between two adjoining rods and formed with opposed rounded grooves receiving said adjoining rods, each section having means to engage the cam.

4. In a device of the class described, a revolving cage comprising a pair of carriers adjustable one toward and from the other and adapted to be journaled on an axial support having a sinuous circumferential cam and penetrating both carriers, rods extending lengthwise of and secured to one and having sliding contact lengthwise of themselves with the other carrier, and means, common to the rods to clamp the rods to the latter carrier, in combination with a shell encompassing said cage and having one end thereof composed of a circumferential series of sections individually movable on the rods toward and from the other end of the shell and each having means to engage the cam.

In testimony whereof I affix my signature.

JOHN E. PETERSON.
